Primary Examiner—Doris V. Coles*Assistant Examiner*—Linda Brooks*Attorney, Agent, or Firm*—Marshall A. Lerner, Esq.; Bradford E. Mattes, Esq.; Kleinberg & Lerner, LLP**[57] CLAIM**

The ornamental design for a drawer and rack for cassette cabinet, as shown and described.

DESCRIPTION

FIG. 1 is a perspective view of a drawer and rack for cassette cabinet showing my new design;

FIG. 2 is a left side elevational view, the opposite side being a mirror image thereof;

FIG. 3 is a top plan view thereof;

FIG. 4 is a front elevational view thereof;

FIG. 5 is a bottom plan view thereof; and,

FIG. 6 is a rear elevational view thereof.

The broken line feature is for illustrative purposes only and forms no part of the claimed design.
